UNITED STATES PATENT OFFICE

CHARLES JARDINE, OF TOLEDO, OHIO, ASSIGNOR TO MOTO METER GAUGE & EQUIPMENT CORPORATION, OF TOLEDO, OHIO, A CORPORATION OF DELAWARE

DESIGN FOR A RADIATOR CAP ORNAMENT

Application filed December 19, 1931. Serial No. 42,141. Term of patent 7 years.

To all whom it may concern:

Be it known that I, CHARLES JARDINE, a citizen of the United States of America, residing at Toledo, Ohio, have invented a new, original, and ornamental Design for a Radiator Cap Ornament, of which the following is a specification, reference being had to the accompanying drawings, forming part thereof.

Fig. 1 is a perspective view of a radiator cap ornament embodying my new design; Fig. 2 is a rear elevation of the same.

I claim:

The ornamental design for a radiator cap ornament, as shown.

In testimony whereof I have signed my name to this specification.

CHARLES JARDINE.
